UNITED STATES PATENT OFFICE

96,459

DESIGN FOR A TEXTILE FABRIC

Curt Erwin Forstmann, Montclair, N. J.

Application June 13, 1935, Serial No. 57,248

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises parallel rows of joined

configurations, elevated with respect to a background, the latter between said rows appearing as sinuous stripes consisting of coarse parallel stria running perpendicular to the direction of the rows, the configurations being of irregular diamond shape with blunt apices, and consisting of short loosely woven loops, irregularly relatively disposed, the configurations having an appearance suggestive of the drupelets of a berry.

I claim:

The ornamental design for a textile fabric as shown and described.

CURT ERWIN FORSTMANN.
